UNITED STATES PATENT OFFICE.

ALEXANDER T. KASLEY, OF ESSINGTON, PENNSYLVANIA, ASSIGNOR TO WESTINGHOUSE ELECTRIC & MANUFACTURING COMPANY, A CORPORATION OF PENNSYLVANIA.

STEAM-CHEST CONSTRUCTION FOR TURBINES.

Application filed October 4, 1921. Serial No. 505,276.

To all whom it may concern:

Be it known that I, ALEXANDER T. KASLEY, a citizen of the United States, and a resident of Essington, in the county of Delaware and 5 State of Pennsylvania, have invented a new and useful Improvement in Steam-Chest Constructions for Turbines, of which the following is a specification.

My invention relates to a steam chest construction for turbines and it has for its object to provide apparatus of the character designated, and shall be simple, compact and inexpensive in construction and effective in 10 operation.

15 In the accompanying drawing, Fig. 1 is an end view of a turbine, partially in section and partially in elevation, and having a steam chest applied thereto constructed in accordance with one form of my invention 20 and Fig. 2, is a detail sectional view of a modification of the steam chest construction shown in Fig. 1.

It is well known that steam turbines are ordinarily provided with steam chests from 25 which the steam is admitted to primary and secondary nozzle blocks by means of appropriate control valves. The steam chests which have heretofore been constructed for this purpose have in general taken the form 30 of rather complicated and expensive castings, inasmuch as it has been usual to incorporate complicated valve structures in the body of the casting.

In accordance with the present invention, 35 I provide a steam chest of simple and inexpensive type in that two flat plates of boiler iron or plate steel are cut to appropriate size and mounted together with a side-wall structure therebetween to make up the body of the steam chest. Aligned valve ports are 40 formed in these two plates and the entire structure is fastened directly to the nozzle deck with bonnets surmounting the upper valve ports. Spool valves are placed in the 45 respective sets of aligned valve ports and appropriate means are provided for permitting the flow of steam admitted under said bonnets through said chest structure to the appropriate nozzle blocks.

50 By this construction, expensive and special castings are entirely avoided and furthermore the danger of hidden flaws is largely eliminated by the use of rolled or forged metal.

55 Referring to Fig. 1 of the drawing for

more detailed understanding of my invention, I show the wall of a turbine stator at 10, provided with fixed blading 11 and surrounding a spindle 12 provided with moving blading 13. A primary nozzle block 14 and 60 a secondary nozzle block 15 of any desired construction face the moving plates 13 which are, for example, of the impulse type.

A steam chest 34 surmounts the turbine and is formed of a flat upper plate 35 and a similar lower plate 16, these plates being formed, for example, of ordinary boiler iron. A side wall or hoop 17, taking for example, the form of a forged ring with planed edges, 65 is clamped between the plates 35 and 16 and 70 by bolts 18-18 and preferably the edges of the ring 17 are sealed by means of copper wire gaskets 19-19 as has for many years been common in locomotive steam chest practice where slide valves are employed. 75

The nozzle blocks 14 and 15 together form a nozzle deck abutting against the lower surface of the plate 16 and they are fastened directly to said plate as by studs 20-20, the steam chest thus forming the main support 80

85 for the steam nozzles. A primary valve port 21 is provided in the plate 16 and an additional primary valve port 22 is provided in alignment therewith in the upper plate 35. These valve ports are appropriately bushed, as is common in the art, and receive a hollow spool valve 23 under the control of suitable operating means 24 and a guide member 26 so that the spool valve 23 substantially simultaneously controls the flow of steam through the ports 21 and 22, as is usual in balanced valve practice. It will be obvious that steam flowing from the steam chest through the port 22 into the space under the bonnet 25 is permitted to flow through the interior of the spool valve 23 to the nozzle block 14 into which the steam admitted through the port 21 flows directly. 95

In like manner, secondary valve ports 27 and 28 are associated with a secondary valve member 29, a bonnet 30, and a guide member 31. 100

Steam is admitted to the valve chest structure through an opening 32 in the upper plate and a pipe 33 having a flanged end fastened directly to the plate 35 as by suitable studs. 105

Having thus described the arrangement of 110 a steam chest constructed in accordance with

my invention, the operation thereof will be obvious. The steam chest is normally filled with steam at boiler pressure and upon opening of the primary valve, either by hand or 5 by the governor, steam flows directly to the primary nozzle block 14 through the port 21 and indirectly through the port 22 and the interior of the spool valve 23. In like manner the opening of the secondary spool 10 valve 29 admits steam directly to the secondary nozzle block 15 through the port 27 and indirectly through the port 28 and the interior of the spool valve 29.

The cost of the stock material for the construction of a steam chest of the character indicated is trivial and the machine work is of the most elementary character so that it is an easy matter to construct a steam chest of any desired size or shape without the use 20 of expensive patterns and castings. All parts are of readily ascertainable and dependable strength so that the danger of failure by explosion is largely minimized. By the usual lagging material, a smooth and pleasing external appearance is secured.

Referring to the form of my construction shown in Fig. 2, top and bottom plates 35 and 16 are employed as before, but the side-wall construction takes the form of a forged 30 channel ring 40 having the flanges thereof joined to the plates 35 and 16 as by rivets 41-41.

Primary and secondary valves are provided as before in suitable bonnets 25 and 35, the spool valves 42 and 43, however, being of the simple spool type, rather than of the hollow type.

A set of hollow studs 44-44 surrounds the primary valve and penetrates both the upper and lower plates of the steam chest and also the nozzle deck so that the openings therethrough furnish communication between the space under the bonnet 25 and the interior of the primary nozzle block. These 45 studs are preferably expanded in place in any desired manner similar to boiler tube practice and they are thus not only readily rendered steam tight but they also serve to firmly join the upper and lower walls of the steam chest and to firmly attach the nozzle block to the steam chest.

In like manner, the secondary valve 43 is associated with hollow studs 45-45 forming 55 passages between the space under the bonnet 30 and the interior of the secondary nozzle block.

Steam is shown as admitted to the chest in Fig. 2 through the lower plate thereof, as at 46.

The operation of the structure thus shown 60 will be obvious. Upon the opening of the primary valve, steam flows directly through the lower port thereof and indirectly through the upper port to the space under the bonnet 25 and downwardly through

studs 44-44 and into the interior of the primary nozzle block and likewise with respect to the secondary valve.

It will be obvious that steam may be admitted to the steam chest either through 70 the top or bottom thereof or through the side wall with but slight modification of the machining operations and without the necessity of expensive special patterns and castings. Thus steam may be admitted 75 through the top of the steam chest of Fig. 2 as shown in dotted lines at 47.

While I have shown my invention in but two forms, it will be obvious to those skilled in the art that it is not so limited, but is susceptible of various other changes and modifications without departing from the spirit thereof, and I desire, therefore, that only such limitations shall be placed thereupon as are imposed by the prior art or as 80 are specifically set forth in the appended claims.

What I claim is:—

1. In a pressure chest construction for fluid pressure turbines, the combination 90 with an outer plate, of an inner plate, a sealing wall structure therebetween to form a closed chamber, aligned valve seats in said two plates, a spool valve operable in said seats, and means providing a path for fluid 95 flow for the fluid passed through said outer plate to the inner side of the inner plate.

2. In a steam chest for steam turbines, the combination with an outer plate, of an inner plate, a side wall structure fastened 100 between said plates, aligned valve ports in said two plates, the port in said inner plate opening to a steam nozzle and the port in said outer plate opening within a bonnet mounted over the port in said outer plate, a spool 105 valve operable to close said ports substantially simultaneously, and means providing a steam passage from within said bonnet to said steam nozzle.

3. In a steam chest for steam turbines, the combination with an outer plate, of an inner plate, a sidewall structure fastened between said plates, aligned valve ports in said two plates, the port in said inner plate opening to a steam nozzle and the port in said outer plate opening within a bonnet seated over the port in said outer plate, a spool valve operable to close said ports substantially simultaneously, and means providing 110 a steam passage from within said bonnet to said steam nozzle, through said steam chest.

4. In a steam chest for steam turbines, the combination with an outer plate, of an inner plate, a sidewall structure fastened between said plates to form a closed chamber, aligned valve ports in said two plates, a bonnet seated over the port in said outer plate and the port in said inner plate opening into a nozzle block, hollow studs 125 pene- 130

trating said plates adjacent said valve seats, the openings in said studs communicating with the interiors of said bonnet and of said nozzle block respectively, and a spool valve adapted to control the steam flow through said ports.

5. In a pressure chest construction for fluid-pressure turbines, the combination with an outer plate, of an inner plate, a sealing wall structure therebetween to form a closed chamber, aligned valve seats in said two plates, a spool valve operable in said seats, and means for admitting the fluid supply through one of said plates.

15 6. In a steam chest construction for steam turbines, the combination with a boxlike structure, of aligned valve ports in the top and bottom thereof, a bonnet covering the port in the top, a spool valve seated in said ports, means for conveying the steam released through the top of said valve when open to the bottom of said chest, and means for admitting steam to said chest.

7. In a steam chest construction for steam turbines, the combination with a boxlike structure having aligned valve ports in the top and bottom thereof, of a spool valve seated in said ports, a bonnet surmounting said top and covering the port therein, hollow studs penetrating said top and bottom, the openings therein communicating with the space beneath said bonnet, and means for admitting steam to said chest.

8. In a steam chest construction for steam turbines, the combination with a boxlike structure having aligned valve ports in the top and bottom thereof, of a spool valve seated in said ports, a bonnet surmounting said top and covering the port therein, and hollow studs penetrating said top and bottom, and expanded into openings therethrough.

9. In a steam chest construction for steam turbines, the combination with a boxlike structure having aligned valve ports in the top and bottom thereof, of a spool valve seated in said ports, said structure surmounting a nozzle block having an opening thereinto aligning with said bottom valve port, a bonnet surmounting said structure over said top valve port, hollow studs adjacent said valve and penetrating the top and bottom of said structure and the nozzle block, the openings in said studs communicating with the space under said bonnet and with the interior of said nozzle block, said studs being expanded in place to firmly

hold said structure to said nozzle block, and means for admitting steam to said boxlike structure.

10. In a steam chest construction for steam turbines, the combination with an outer plate, of an inner plate, a side-wall structure fastened between said plates to define a boxlike structure, aligned valve ports in said outer and inner plates, a spool valve seated in said ports, a nozzle block seated against said inner plate and having an opening thereinto aligning with said inner valve port, a bonnet fastened to said outer plate covering the port therein, hollow studs adjacent said valve and penetrating said inner and outer plates and said nozzle block, the openings in said studs communicating with the space under said bonnet and with the interior of said nozzle block, said studs being expanded in place to firmly engage said nozzle block to said inner and outer plates, and means for admitting steam to said chest through one of said plates.

11. In a steam chest construction for steam turbines the combination with a boxlike structure having two sets of aligned valve ports in the top and bottom thereof, respectively, of a primary spool valve seated in one of said sets of ports and a secondary spool valve seated in the other of said sets of ports, a primary nozzle block and a secondary nozzle block forming a nozzle deck in contact with the bottom of said structure, the lower primary valve port aligning with an opening into the primary nozzle block and the lower secondary valve port aligning with an opening in said secondary nozzle block, respectively, a bonnet surmounting said structure over each of said outer valve ports, respectively, a set of hollow studs adjacent each of said valves, respectively, said studs penetrating the top and bottom of said structure and said nozzle deck, the openings through the studs associated with the primary valve communicating with the space under the primary valve bonnet and with the interior of the primary nozzle and similarly with respect to the studs associated with the secondary valve, said studs being expanded in place to firmly engage said structure with said nozzle deck, and means for admitting steam to said boxlike structure.

In testimony whereof, I have hereunto subscribed my name this 28th day of September, 1921.

ALEXANDER T. KASLEY.
